Patented Dec. 23, 1919.

UNITED STATES PATENT OFFICE.

HENRY G. RUNNE, OF ROCHESTER, NEW YORK, ASSIGNOR OF ONE-HALF TO CHARLES L. TOWNSEND, OF ROCHESTER, NEW YORK.

VEHICLE.

1,325,583.

Specification of Letters Patent. Patented Dec. 23, 1919.

Application filed May 6, 1919. Serial No. 295,055.

To all whom it may concern:

Be it known that I, HENRY G. RUNNE, a citizen of the United States, and a resident of Rochester, in the county of Monroe and State of New York, have invented certain new and useful Improvements in Vehicles; and I do hereby declare the following to be a full, clear, and exact description of the same, reference being had to the accompanying drawings, forming a part of this specification, and to the reference-numerals marked thereon.

My present invention relates to vehicles and more particularly the steering mechanism thereof and it has for its object to provide an improved adjustable steering post of such simplicity and cheapness as to make it available for use in connection with toy vehicles such as velocipedes and the like that are inexpensively built and assembled and adjusted by unskilled persons. The improvements are directed toward the means provided for elevating or lowering the vehicle body upon the steering post and to these and other ends the invention resides in certain improvements and combinations of parts all as will be hereinafter more fully described, the novel features being pointed out in the claims at the end of the specification.

30 In the drawings:

Figure 1 is a side view of a toy vehicle constructed in accordance with and illustrating one embodiment of my invention;

Fig. 2 is an enlarged bottom view of a fragment of the body taken in horizontal section through the steering post;

Fig. 3 is a fragmentary section taken substantially on the line 3—3 of Fig. 2, and

Fig. 4 is an enlarged perspective view of a bracket bearing for the steering post.

Similar reference numerals throughout the several views indicate the same parts.

In the present instance, the vehicle consists of a body or seat board 1 which is straddled by the child who pushes against the ground with his feet to obtain locomotion. At the rear end of the body there is pivoted at 2 an axle board 3 carrying the axle 4 supported by rear wheels 5. A radius rod 6 adjustable as to length in a manner not here involved, connected to the axle 4 and to the under side of the body controls the angle of the axle board 3 and hence the height at which the rear end of the body is supported. These changes necessitate a corre-

sponding change in elevation of the front end of the body which is supported upon a steering post 7 having a handle 8 at the top and a fork 9 at the bottom provided with an axle 10 for the single front wheel 11 and it 60 is these changes in the adjustment of the steering post or in the adjustment of the body thereon with which my present invention has to do.

The said steering post 7 extends vertically 65 or at a slight inclination through the body and is provided in this region with a number of circumferential grooves 12 forming annular seats or shoulders. It also extends through the offset portion 13 of a bracket 70 plate 14 that is secured to the under side of the body 1 and the said offset portion 13 is apertured at 14^a to receive it, as shown in Fig. 4, the aperture being defined by an upstanding collar 15 that constitutes a bearing for the post in addition to the bearing provided by the body itself, as shown in Fig. 3. The radius rod 6 may also be pivoted at 16 at its front end to the plate 14 which, in the present instance, is provided with an ear 17 for this purpose. In the form shown, the bracket plate is secured to the body board firmly by screws 18. The offset portion 13 of the bracket is 75 preferably annular and at one side there is pivoted to and beneath the same as at 19, a semi-annular locking member 20. This member 20 is preferably of substantially the contour of the member 13 and is adapted to be swung from the inoperative position of 80 Fig. 4 to the operative position of the other figures, whereupon an aperture 21 in its opposite or free end comes into register with an aperture 22 in the offset portion 13 to receive a cotter pin or other device 23 and 85 be secured in locked position. The manipulations of the locking member are conducted by means of an ear 24 that constitutes a handle and w^h because of the offset formation of the plate 14, is at all times readily accessible. When moved to locking position, the locking member 20 cooperates, selectively, with any desired one of the plurality of annular seats or shoulders 12 on the post 7 so that the body is supported at the front 90 through the medium of the locking member at the desired height to conform to the height of the rear end that has previously been adjusted according to the reach of the child's legs. The semicircular portion or 105 110

inner curve of the locking member 20 is, of course, on a shorter radius than that of the aperture 14^a of the bracket so that it will reach well within the groove or seat 12 5 on the post and provide a substantial supporting surface.

A device constructed in accordance with my invention is provided with the aid of a few simple sheet metal stampings and can 10 be readily adjusted by unskilled persons who, in order to effect a change of adjustment, are required to merely remove the cotter pin 23 and replace it after swinging out the member 20 and seating it in the 15 desired groove.

I claim as my invention:

1. The combination with a vehicle body and a rotatable steering post extending through the body and vertically adjustable 20 relatively thereto, of a member pivoted to the body and adapted to be swung into and out of locking engagement with the steering post, to rotatively support the body thereon.
2. The combination with a vehicle body 25 and a rotatable steering post vertically adjustable relatively thereto and provided with a plurality of annular seats, of a member pivoted to the body and adapted to be swung into and out of locking engagement with 30 said seats, selectively, to rotatably support the body at different heights on the steering post.
3. The combination with a vehicle body

and a rotatable steering post vertically adjustable relatively thereto and provided with a plurality of annular seats, of a semi-annular member pivoted to the body and adapted to be swung into and out of locking engagement with said seats, selectively, to rotatably support the body at different heights on 35 the steering post.

4. The combination with a vehicle body having an offset bracket thereon and a rotatable steering post extending through the body and bracket to be vertically adjustable 40 relatively thereto and provided with a plurality of annular seats, of a member pivoted to the bracket and adapted to be swung into and out of locking engagement with said seats, selectively, to rotatively support the 45 body at different heights on the steering post.

5. The combination with a vehicle body and a steering post vertically adjustable relatively thereto and provided with a plurality of annular seats, of a bracket secured 50 to the body and embodying an offset apertured portion provided with a collar forming a bearing for the steering post, and a curved member pivoted to such offset portion and adapted to be swung into and out of locking engagement with said seats on the steering post, selectively, to rotatably support the body at different heights on 55 the steering post.

HENRY G. RUNNE.
